WASH FOUNTAIN SPRAY HEAD

Howard G. Mullett and Edward D. Wachter, Jr.,
Whitefish Bay, Wis., assignors to Bradley Wash-
fountain Co., Milwaukee, Wis., a corporation of
Wisconsin

Application October 23, 1946, Serial No. 705,050

1 Claim. (Cl. 4—145)

1

The invention relates to sprayheads for wash-
fountains.

One object of the invention is to provide a
new and improved arrangement for mounting
a sprayhead on a washbasin.

A further object of the invention is to provide
a two-part sprayhead in which one of the parts
is clamped in water-tight relation with the supply
pipe by an apertured nut and in which the
other part of said sprayhead is clamped to the
first part by a screw engaging said nut.

The invention further consists in the several
features hereinafter set forth and more partic-
ularly defined by claims at the conclusion
hereof.

In the drawings:

Fig. 1 is a front elevation view of the sprayhead
structure embodying the invention;

Fig. 2 is a vertical sectional view taken on the
line 2—2 of Fig. 1;

Fig. 3 is a horizontal sectional view taken on
the line 3—3 of Fig. 1;

Fig. 4 is a plan view of a washfountain equipped
with a sprayhead embodying the invention.

Referring to the drawings, the numeral 5
designates a washbasin and 6 our improved spray-
head mounted on the back portion 7 of said basin
and provided with peripheral spray orifices here-
inafter described to distribute water sprays over
substantially the entire area of the bowl of said
basin.

The spray nozzle is formed of two cup-shaped
parts 8 and 9 whose dished portions form a
cavity 10. The lower base member 8 of the
nozzle is a cylindrical cup-shaped member having
a central aperture 11 and a recessed peripheral
edge 12 providing a centering surface and a
shoulder 13. For a portion of its circumference
the top edge of said cup is provided with a series
of radially disposed grooves 14 which when the
inverted cup or cap 9 is clamped in position, form
spray orifices to distribute the water over the
bowl of the basin 5.

For mounting the nozzle above described on the
basin 5 and supplying water thereto, a hollow
cylindrical supporting sleeve 15 is interposed be-
tween the basin 5 and the back portion 7 of the
basin, and the recessed edge 12 of the member
8 fits within the top of said sleeve with its
shoulder 13 abutting the top of said sleeve, and
a water supply pipe 16 is used as a tie bolt to
clamp these parts together in assembled relation
with said basin. For this purpose the pipe 16 is
threaded and extends up through an opening 17
in the back 7 of the basin to which it is clamped
by washers 18 and nuts 19 disposed on opposite
sides of and operatively engaging said basin, and

5 a cap nut 20 and washer 21 are mounted on the
upper end of said pipe 16 and clampingly engage
the apertured bottom of the member 8. Thus the
pipe 16 is firmly anchored to the basin and in
turn through the sleeve 15 and the nut 20 firmly
clamps the lower base member 8 of the nozzle
to the basin, the nut 20 having one or more open-
ings 22 therein to conduct the water from the
pipe 16 into the cavity 10.

10 The cap 9 is provided with a central opening
23 through which a screw 24 having threaded
engagement with the upper portion of the nut
20 passes whereby said cap 9 is clamped to the
member 8 and also to the supply pipe 16 through
15 said screw.

With the above construction the spray nozzle is
supported above the basin in proper spaced rela-
tion relative to the bowl, so that its sprays will
fall gently into the bowl when the nozzle is in
20 operation and there is very little machine work
required to fit the above named parts together.

We desire it to be understood that this invention
is not to be limited to any particular form
or arrangement of parts except in so far as such
25 limitations are included in the claim.

What we claim as our invention is:

In a sprayhead structure for washfountains
having a supply pipe anchored to a wall of the
washbasin and having a threaded portion project-
30 ing above the same, the combination of a pair
of cup-shaped members having their peripheral
edges in abutting relation and forming a cavity
35 provided with spray outlets at their peripheral
edges, said pipe extending through a central
opening in one of said members, a hollow sup-
porting sleeve for said members, means for cen-
40 tering one of said members relative to the top
of said sleeve, an apertured cap nut on said
supply pipe for clamping said centered member
against the top of said sleeve and to said supply
45 pipe, and means for clamping the other of said
members in assembled relation and to said nut.

HOWARD G. MULLETT.
